GEORGE A. BURNHAM, OF SAUGUS, MASSACHUSETTS, ASSIGNOR TO CONDIT ELECTRICAL MANUFACTURING CORPORATION, OF SOUTH BOSTON, MASSACHUSETTS, A CORPORATION OF MASSACHUSETTS

ELECTRIC SWITCH

Application filed April 14, 1926. Serial No. 102,071.

This invention relates to oil-immersed high tension electric switches.

The terminals of an electric switch must have sufficient spacing to prevent flash-overs between them, and where air is the insulating medium, the terminals must necessarily be spaced widely apart to provide sufficient insulation, if high voltages are employed. To provide the requisite spacing with vertically disposed insulating bushings would necessitate switch casings of prohibitive size; so it has been common practice to obtain the desired spacing at the terminal end of the bushing by inclining the bushings outwardly.

This construction, while providing an increased spacing at the top of the insulator, must necessarily decrease the spacing at the lower end of the insulator. To a certain extent this may be permissible since the lower exposed terminals of the insulator are immersed in oil; but it is evident that if the bushings are inclined to any great extent, the lateral dimensions of the switch casing must be increased to maintain a safe spacing of the lower terminals.

An object of this invention is the provision of an electric switch and insulating bushings for the switch studs so arranged that a relatively wide spacing of the exposed terminals of the studs is provided with a switch casing of moderate dimensions.

A further object is generally to improve the construction of high tension electric switches and similar apparatus.

Certain features herein described are described and claimed in my co-pending applications Serial No. 729,625, filed August 1, 1924, and Serial No. 102,069, filed April 14, 1926.

Fig. 1 is a sectional elevation of an electric switch embodying the invention.

Fig. 2 is a sectional elevation through an insulating bushing of Fig. 1.

Fig. 3 is a sectional elevation of a modified form of electric switch embodying the invention.

The electric switch illustrated in Fig. 1 includes an enclosing casing comprising the oil receptacle 10 and the switch frame 12 which forms a cover for said receptacle. Said frame

is provided with a top wall which has two downwardly inclined opposed sections 14 and 16 each formed with an aperture there-through. A mechanism well 18 is carried by the switch frame under the top wall and about in the vertical line of the casing, and suitable operating mechanism 20 is contained therein. A movable switch member 22 is connected with said mechanism and depends therebelow and is provided at its lower end with a bridging, as a brush, member 24. The stationary switch members 26 each comprise a bent metal tube 28 so shaped as to provide an approximately vertical lower section 30 and an outwardly inclined upper section 32 which is approximately perpendicular with an inclined section of the top wall of the switch frame. Said tube extends through the aperture in said inclined section and depends therebelow and is provided with an outstanding flange 34 at its upper end which covers said aperture and is secured to said wall by bolts 36. A tubular insulating body or shell is disposed on the upper end of said tube and in line with the opening therein and has a clamping flange 38 at its lower end which is secured to said flange 34 by bolts 40. As thus arranged, said insulator-shell is extended upward and at an angle outward away from the vertical axis of the casing. Said shell may be provided with suitable petticoats 42 and has a terminal-connector 44 at its top. A second tubular insulator-body or shell 46 is vertically disposed within the switch casing and has a clamping ring 48 fixed to its upper end; and said clamping ring is attached by bolts 50 to an outstanding flange 52 formed at the lower end of said tube, thereby to secure said shell to said tube in line with the opening therein. A contact member 54 is carried by the lower end of said shell and is adapted to be engaged by the movable switch member to control the circuit through the switch. The insulator thus described is provided with a conductor-structure illustrated more particularly in Fig. 2 as comprising a conductor 56 which extends through said insulator approximately co-axially therewith and is connected to said contact block and the upper terminal member of the

insulator. A body of insulation 58, as a cylindrically-formed multi-layered body of paper, surrounds said conductor approximately co-extensive therewith. A metal sheath surrounds the middle portion of said body of insulation and occupies said bent tube. The exposed ends of said body of insulation beyond said metal sheath and within said insulator shells may be tapered as illustrated. The conductor-structure above described is bent or shaped to enter the insulator and conform in shape therewith. Preferably said conductor-structure is formed from a section of commercial high tension cable and shaped as above described and as set forth more specifically in my above-named copending applications.

By the provision of the insulators above described, the lower ends thereof may be vertical and relatively closely spaced under the oil, so that the casing may be of moderate diameter, while preserving adequate insulation between the casing and conducting components of the switch. At the same time the exposed insulator terminals may be widely spaced in air and thus may be well insulated against flashovers therebetween.

The oil level in the casing is adapted to be somewhat above the lower ends of the metal tubes of the insulators whereby to prevent corona thereat.

In the switch illustrated in Fig. 3 the switch frame is modified to take the place of the metal tubes of Figs. 1 and 2. As illustrated in this figure the switch frame 12^a is formed with the horizontal bottom wall 60 and the top wall 62 which is spaced above said bottom wall and is provided with the opposed and downwardly-inclined wall-section 64 and 66. The walls 68 of a mechanism well 70 connect the top and bottom walls and divide the space therebetween into two compartments 72 and 74, each of which is equivalent to the metal tube of Figs. 1 and 2. Insulators 76 and 78 are carried by said top and bottom walls, respectively, and conductor-structures 80 extend through said insulators and the compartments 72 and 74 and are connected with terminal-connectors 82 at the tops of said insulators 76 and with contact blocks 84 at the bottoms of said insulators 78.

The construction may be otherwise modified without departing from the spirit of the invention.

55 I claim:

1. In an electrical apparatus, the combination of an enclosing casing, approximately vertical insulator-bodies carried by and depending within said casing, companion insulator-bodies carried by said casing and extended upwardly and outwardly therefrom in angular relation to said first insulator-bodies, terminal connectors carried by the lower ends of said first insulator-bodies, and bent continuous conductors extended

through said vertical and companion insulator-bodies.

2. In an electrical apparatus, the combination with an oil-containing casing, of a pair of insulator bushings having their exposed portions extending upwardly from the casing in diverging relation, each bushing comprising angularly-related insulator-bodies having communicating passages therein and carried on opposite sides of a casing-wall, one of which is extended below the oil level in the casing and is provided with a terminal connector at its lower end, and a bent continuous conductor extended through the communicating passages in said insulator-bodies and having a connection with said terminal connector.

3. An electric switch comprising the combination with an enclosing casing of a pair of insulator bushings having their exposed portions extending upwardly from the casing in diverging relation, each bushing comprising an approximately-vertical insulator-body carried by and depending within said casing, a second insulator-body carried by said casing and extended outwardly therefrom at an angle with said first insulator-body, and a continuous conductor extended through both insulator-bodies.

4. An electric switch comprising the combination with an enclosing casing of a pair of insulator bushings having their exposed portions extending upwardly from the casing in diverging relation, each bushing comprising an approximately-vertical insulator-body carried by and depending within said casing, a second insulator-body carried by said casing and extended outwardly therefrom at an angle with said first insulator-body, a contact member carried by the lower end of said first insulator-body, a movable switch member cooperating with said contact member, and a bent continuous conductor extended through both insulator-bodies and having a connection with said contact member.

5. An electric switch comprising the combination of an enclosing casing, a pair of insulating bushings extended through said casing, said bushings having approximately vertical and parallel lower insulating sections and divergent upper insulating sections, and switch mechanism disposed between said bushings above the vertical sections thereof.

6. An electrical apparatus having the combination of an enclosing casing and a pair of insulated terminals therefor, each terminal comprising a bent tube extended through said casing and having an approximately vertical lower section and an upper section which is inclined away from the vertical lower section, an insulator-body attached to and depending from the end of said vertical section in line therewith, a ter-

55 5. terminal connector carried by said insulator body at its lower end, a second insulator-body attached to the end of said upper inclined section and extended upwardly therefrom and above the casing and at an inclination from the vertical and a bent conductor extended through said tube and insulator-bodies and having a connection with said terminal-member.

60 6. 7. An electric switch having the combination with an oil-containing casing of a pair of insulator bushings having their exposed portions extending from the casing in diverging relation, each bushing comprising a bent tube carried by said casing and having a lower vertical section which extends below the oil level in said casing and an upper section which is inclined away from the vertical, an insulator-shell attached to the end 65 of and depending below and in line with said vertical section, a contact member carried by the lower end of said tube, a second insulator-body attached to the end of and extended upwardly beyond said inclined section at an 70 inclination with said casing, a bent conductor extended through said tube and said insulator-bodies and having a connection with said contact member, and a movable switch member cooperating with said contact 75 member.

80 8. An electric switch having the combination with an oil-containing casing of a pair of insulator bushings having their exposed portions extending from the casing in diverging relation, each bushing comprising a bent tube carried by and disposed mainly within said casing, said tube having an approximately vertical lower section and an upper section which is inclined away from the vertical, an insulator-body attached to the end of and depending below said vertical section and in line therewith, a contact member carried by the lower end of said insulator-body, a second insulator body connected with the 85 end of said inclined section and extended outwardly in line therewith and upwardly above and at an inclination with said casing, a bent conductor extended through said metal tube and insulator-bodies and having a connection with said contact member, and a movable switch member cooperating with said contact member.

90 9. An electric switch comprising an oil casting having a pair of switch terminals, each 95 terminal comprising an insulating bushing having a metal shell provided with an approximately vertical lower section and an upper section which is inclined away from the vertical, an insulator-shell attached to the 100 end of and depending from said vertical lower section, a contact member carried by the lower end of said insulator-shell, a second insulator shell attached to the end of and extended upwardly from and in line with 105 said upper section, a bent conductor extended

110 through said metal and insulator-shells and having a connection with said contact member, a movable switch member cooperating with said contact member, and supporting means for said bushing having a connection 115 with said metal shell and with said casing.

120 In testimony whereof, I have signed my name to this specification.
